(57) **CLAIM**

The ornamental design for a food pickup locker, as shown and described.

DESCRIPTION

FIG. 1 is a front perspective view of a food pickup locker showing our new design;

FIG. 2 is a front view of the food pickup locker;

FIG. 3 is a rear view of the food pickup locker;

FIG. 4 is a left side view of the food pickup locker;

FIG. 5 is a right side view of the food pickup locker;

FIG. 6 is a top view of the food pickup locker;

FIG. 7 is a bottom view of the food pickup locker; and,

FIG. 8 is another front perspective view of the food pickup locker.

The broken lines are included for the purpose of illustrating unclaimed portions of the food pickup locker and form no part of the claimed design. The stippling in the drawings depicts a contrast in appearance.
